EARTH TAMPING DEVICE

John A. McDougall and Robert E. McGary,
Portland, Oreg.

Application October 15, 1938, Serial No. 235,265

7 Claims. (Cl. 61—63)

This invention relates to means for tamping earth on sloping embankments, inclined walls and bottoms of canals, excavations, etc., on which concrete surfacing is to be placed. In such work it generally becomes necessary to tamp the earth thoroughly first before the concrete surfacing is applied.

While various tamping means, which are more or less practical, have been devised for horizontal surfaces, these means are not efficient for use on sloping surfaces, such as those above mentioned. Consequently, it has been necessary, as well as customary, up to the present time, when preparing the surface of canals, reservoirs, earth filled dams and dykes, and similar excavations, and other embankments for concrete lining, to have the tamping performed by manual labor. This procedure is slow and expensive as well as inefficient.

The object of this invention is to provide a machine-operated tamping device which is especially adapted for use on sloping surfaces of excavations and embankments, by means of which the desired tamping of such surfaces can be done more efficiently and economically.

A further object of this invention is to provide a tamping device of this nature suitable for sloping embankments, and the like, which will be simple in construction, easy to operate, and which can be set up without difficulty and readily moved from place to place as the work progresses.

These and other objects we attain by providing a movable carriage on which is mounted a power-driven hammer, a rigid supporting structure supporting tracks for the carriage and adapted to hold the carriage always spaced a proper distance from the surface to be tamped, power means carried on the supporting structure for moving the carriage thus transversely across surfaces to be tamped while at the same time operating the power-driven hammer, a tamping shoe actuated by the hammer and contacting the surface to be tamped, and other parts, all of which will be apparent from the following brief description with reference to the accompanying drawings.

In the drawings:

Fig. 1 is an assembly view showing an embodiment of our invention in operation in a canal excavation;

Fig. 2 is an enlarged sectional elevation taken on the plane of line 2—2 in Fig. 1;

Fig. 3 is a vertical section taken on the plane of line 3—3 of Fig. 2;

Fig. 4 is a side elevation of the compressed air

hammer and earth tamping shoe, these elements being detached and enlarged from the assembly Fig. 1 for purposes of clarity;

Fig. 5 is a detail plan view of the tamping shoe;

Fig. 6 is a vertical transverse section corresponding to the line 6—6 of Fig. 5 but drawn to a larger scale; and

Fig. 7 is an assembly view illustrating a modified form of our invention in operation on an earth embankment such as the face of a reservoir, 10 dyke, or the like.

Referring first to Fig. 1, the entire apparatus for tamping the inclined sides and the bottom of a canal or other excavation is carried on a rigid frame made to conform in general shape to 15 the transverse contour of the excavation and adapted to travel on rails C laid on the berm grade or terrace of the canal. This frame consists of a pair of inverted trusses A firmly secured together in spaced parallel relationship by suitable connecting members (not shown) and mounted on two pairs of double-flanged wheels B, each pair being arranged in tandem, and each pair rolling on the rail C accurately laid at each side of the top of the sides of the canal to coincide 25 with the finished grade.

A set of guides consisting of two pairs of channel members is disposed between and firmly secured to the trusses A in parallelism with the sides and bottom of the excavation, each pair of 30 guides comprising a lower channel D and an inverted upper channel E (see also Figs. 2 and 3). These four channel members serve to guide the movement of a carriage F in its travel transversely of the ditch and at a uniform distance from 35 the sides and bottom thereof.

The carriage F comprises two substantial axles 10 and 11 (Fig. 3), carried on two pairs of rubber-tired wheels 12 and 13 adapted to roll in the channel guides D and E; a rigid guide frame 14 40 supported in a central position between the said wheels and held perpendicular to the axles 10 and 11 by suitable bracing members 14' secured to the axles; and a chassis 15 firmly attached to the braces 14'.

A compressed air hammer 16, similar to the type in conventional use for driving piles is reciprocally disposed in the guide frame 14. This air hammer has a double-acting ram 17 (see Fig. 3) which is caused to reciprocate in a 50 ported cylinder formed in the body of the hammer by compressed air brought to the hammer by a flexible hose 18 and introduced therein via the usual valve chest 19. The hammer 16 may be held at the desired height in the guide frame 55

- 14 or raised and lowered therein by compressed air connected by a flexible hose 20 to a cylinder 21 mounted on the frame 14, the air being admitted above a piston 22 adapted to reciprocate upon variance of pressure in the top of said cylinder 21, and having an upstanding piston rod 23 which is connected by a wire rope 24 to the top head of the hammer 16, said wire rope being passed over a sheave 25 superimposed on the guide frame 14.
- 10 In operation, the ram 17 delivers rapid blows on a tamping shoe 26 of special design. This shoe, as illustrated in detail in Figs. 5 and 6, is preferably rectangular in plan and has the edges which are parallel to the carriage axles 10 and 11 bent upwardly as shown. A concentric boss 27 is made integral with, or firmly secured to, the shoe 26 and is additionally supported by pairs of longitudinal ribs 28 and transverse ribs 29, the whole being a very rigid structure capable of transmitting, without fracture or bending, the impact of the ram 17 to the earth beneath the shoe and thus compacting it. However, we have found it practical to insert a concussion plug 30 made of wood, soft metal or the like in a tapered hole in the boss 27, the top of the plug 30 being of the same diameter as the ram 17 and extending slightly above the top of the boss 27. A binding band 31 prevents this extending end of the plug from spreading under the blows of the ram. The concussion plug 30 may be readily removed from the shoe 26 when necessary by inserting a suitable punch in a hole 32 provided in the bottom of the shoe. The size, shape and proportions of the tamping shoe 26 may be varied to suit different earth conditions and to give the required number of pounds per square foot pressure proportional to the force exerted by the hammer ram.
- 40 The tamping shoe 26 is normally held against the bottom of the hammer 16 by a pair of substantial compression springs 33 which bear at the lower end on a rigid plate 34 firmly secured to the base of the hammer 16 and at the upper end on shouldered sleeves 35 reciprocally disposed in rigid brackets 16' attached to the hammer body. The sleeves 35 are detachably mounted on the threaded upper ends of tie rods 36 which pass down through the springs 33 and plate 34 and are removably attached to the ribs 28 of the shoe by bolts 37, as seen in Fig. 4. Thus, on the downward stroke of the ram 17, the tie rods 36 are drawn downwardly and the shouldered sleeves 35, sliding in the fixed brackets 16', compress the springs 33. As the ram recedes, the shoe is of course immediately retracted by the extension of the springs 33. Since these tie rods 36 constitute the sole supporting means for the tamping shoe 26, it is necessary to provide means for returning the shoe to the proper position each time relative to the ram 17 so that no twisting force is exerted on the shoe by the subsequent blows of the ram. This we accomplish by tapering the upper portion of the shoe boss 27 to correspond with beveled blocks 38 rigidly secured to the hammer 16 at each corner, these depending blocks fitting into the spaces between the ribs 28 and 29 when the shoe is in retracted position.
- 70 The flexible hoses 18 and 20 of the hammer 16 and cylinder 21 may be connected to any suitable apparatus for furnishing compressed air or steam, and the entire carriage F may be moved back and forth in the guides D and E by any suitable prime mover, but we prefer to carry all

the necessary power furnishing means on the traveling frame composed of the trusses A and thus provide a self-contained machine. Therefore we provide a tank T to which air under pressure is delivered by a conventional engine-driven compressor G, the tank T serving to store the compressed air for the hammer 16, cylinder 21, and also for the carriage moving hoist H and frame moving winch J (see Fig. 1). The carriage moving hoist H is of the dual drum type in which one drum can be made to pay out its line as the other line is wound in. The line 39 runs from one drum around a sheave 40 carried on a suitable braced post at one end of the truss frame to a sheave 41 mounted at the rear end 15 of the carriage-chassis 15 back to another sheave 42 on the truss post and thence to anchorage on the axle 11 of the carriage F (Fig. 3). In similar manner, the other line passes around sheaves 44, 45 and 46 to the carriage axle 10, an additional sheave 47 carrying the line 43 clear of other moving parts. Thus when air under pressure is supplied in the usual manner from the main air pipe K connected to the tank T to the drums of the hoist H, the carriage F may be moved in the guides D and E and caused to ascend or descend the inclined sides of the canal excavation.

In order to keep the flexible hoses 18 and 20 out of the path of the moving carriage F, we provide means for maintaining these hoses reasonably taut. Each of the flexible hoses is clamped as at 48 and 49 in Fig. 2 to the top of the hammer guide frame 14 and extends from there between pairs of grooved wheels 50 mounted on cross members of the trusses and over similar grooved wheels 51 carried on a suitable super-structure to connections with the main air pipe K, the counter-weighted sheaves 52 and 53 taking up the slack in the hoses 18 and 20, respectively. 40

The winch J (Fig. 1) for moving the entire apparatus along the excavation receives compressed air via the branch pipe L and has two drums which wind in tow lines 60 and 61 which pass around sheaves 62 and 63. These hoist drums are rotated at the same speed when it is desired to draw the traveling frame straight ahead, but when rounding a curve in the canal one is rotated faster than the other. The entire apparatus may be controlled by a single operator 50 stationed at any convenient location on the traveling frame by simply providing adjacent valves (not shown) which regulate the passage and supply of compressed air to the several devices. 45

In compacting the earth on the inclined sides and bottom of a canal or other excavation, the apparatus is operated as follows: The carriage F, with the shoe 26 and hammer 16 raised clear of ground by air introduced in cylinder 21, is brought to the base of one of the slopes by the hoist H. Then sufficient air is released from cylinder 21 to allow the shoe 26 to rest on the ground. Compressed air is then introduced into the hammer 16 thus actuating the ram 17 and starting the tamping action and, at the same time, the hoist H is operated to cause the carriage slowly to ascend the slope, the continuous reciprocation of the ram tamping a strip of earth the length of the shoe 26. Upon reaching the 60 top of the slope, the hammer and shoe are raised to clear the earth and the hoist reversed so that the carriage returns to the base of the slope. The hammer is then lowered and set in operation as before and the carriage drawn across the bot- 70 75

tom of the ditch and up the other slope. When this strip of earth has been thus compacted the entire apparatus is moved ahead the length of the tamping shoe by the winch J and the operation previously described repeated.

Thus far we have shown our earth tamping device as adapted to being used for compacting the earth in a canal excavation. However, in a slightly modified form our invention may also be applied to tamping an embankment such as that of a reservoir or earth fill dam. Such a modification is illustrated in Fig. 7. The frame M, consisting of a pair of spaced parallel trusses or other rigid beams, is supported at each end on a pair of tandem wheels N rolling on single rails laid at the top and bottom of the embankment substantially as shown. Channel members O and P similar to the members D and E of Fig. 1 guide and support the carriage F which is identical to that heretofore described with reference to Fig. 1, except that only a single hoisting line Q is required and this is wound or unwound on the drum of the compressed air hoist R. Compressed air is supplied to the several devices by the compressor G and the winch J' pulls the traveling frame ahead as before. The flexible hoses 54 and 55 conveying air under pressure to the hammer 16 and cylinder 21, respectively, are supported in this embodiment by grooved wheels 56 carried on an arm 57 pivotally mounted as at 58 on a suitable fixed post, a connecting tension spring 59 keeping the hoses reasonably taut and clear of the moving carriage F.

Various modifications in the construction of the supporting truss framework and also in construction of the carriage carrying the compacting hammer and shoe may be made without departing from the principle of our invention. It is not our intention to limit our invention otherwise than as set forth in the claims forming part of this application.

We claim:

1. In an earth tamping device for use on a concave ditch surface, a frame extending transversely across said surface, a track supported by said frame, said track following the contour of said surface and held by said frame spaced a uniform distance above said surface, a carriage movable in said track across said surface, means preventing the lifting of said carriage from said track, earth tamping means supported by said carriage at all times, a guide frame on said carriage perpendicular to the plane of travel of said carriage, said tamping means disposed in said guide frame, a tamping shoe carried by said tamping means, means on said carriage for adjusting the position of said tamping means in said guide frame with respect to said surface, means located apart from said carriage for actuating said position adjusting means and for actuating said tamping means.

2. The combination described by claim 1 including springs holding said shoe in place against the bottom of said tamping means.

3. In an earth tamping device for use on a concave ditch surface, a frame extending transversely across said surface, a track supported by said frame, said track following the contour of said surface and held by said frame spaced a uniform distance above said surface, a carriage movable in said track across said surface, said track having top guides to prevent the lifting of said carriage from said track, earth tamping means supported by said carriage at all times, a guide frame on said carriage perpendicular to the

plane of travel of said carriage, said tamping means reciprocably disposed in said guide frame, a tamping shoe at the bottom of said tamping means, springs holding said shoe in place against the bottom of said tamping means, means located apart from said carriage and supported on said track-supporting frame for actuating said tamping means.

4. In an earth tamping device for use on a concave ditch surface, a frame extending transversely across said surface, a track supported by said frame, said track following the contour of said surface and held by said frame spaced a uniform distance above said surface, a carriage movable in said track across said surface, means preventing the lifting of said carriage from said track, earth tamping means supported by said carriage at all times, said tamping means including a guide frame perpendicular to the plane of travel of said carriage, a compressed air hammer slidably disposed in said guide frame, a double-acting ram in said hammer, a tamping shoe carried by said hammer adapted to receive blows from said ram, means on said carriage for adjusting the position of said hammer with respect to said surface, means located apart from said carriage for actuating said position adjusting means and for actuating said ram.

5. The combination described by claim 4 including springs holding said shoe in place against the bottom of said hammer.

6. In an earth tamping device for use on a sloping embankment, a frame extending transversely across said surface, a track supported by said frame, said track held by said frame spaced a uniform distance above said surface, a carriage movable in said track, earth tamping means supported by said carriage at all times, a guide frame on said carriage perpendicular to the plane of travel of said carriage, said tamping means disposed in said guide frame, a tamping shoe carried by said tamping means, springs holding said shoe in place against the bottom of said tamping means, means carried by and operable from said track-supporting frame for operating said tamping means, means carried by and operable from said track-supporting frame for lifting said tamping means out of contact with said surface, and means on said track-supporting frame for moving said carriage in said track.

7. In an apparatus for progressively condensing the surface material of a sharply-inclined earthwork slope such as a wall of a dug canal, a travelling frame of girder-like form provided with an integral trackway and with means for bodily supporting and shifting said frame along said earthwork slope with said integral trackway transversely overlying the slope surface in correspondingly sharply-inclined parallelism thereto, a carriage movable up and down said inclined transverse trackway, a reciprocating ram mounted on said carriage, a tamping shoe associated with said ram for driving thereby into impacting contact with an underlying portion of the slope surface, means for directly coupling said carriage to said inclined trackway and preventing appreciable lifting or canting of said carriage relative thereto regardless of the degree of inclination in said trackway or the amount of reaction developed by said ram during tamping operation, and means for progressively moving said carriage and its mounted ram and tamping shoe along the length of said inclined trackway as impact of the overlain slope surface is effected by said tamping shoe, said last mentioned

means comprising a prime mover directly supported upon the frame proper remote from said carriage, a cable take-up and pay-out mechanism directly mounted upon said frame proper remote from said carriage and actuated by said prime mover, and a flexible cable coupled to said

carriage and extending to said take-up and pay-out mechanism for transmitting progressive movement to said carriage as slope impaction proceeds.
